UNITED STATES PATENT OFFICE.

JOHN H. SARGENT, OF PHILLIPSBURG, NEW JERSEY, ASSIGNOR OF ONE-HALF TO
WILLIAM M. RODGERS, OF PHILLIPSBURG, NEW JERSEY.

DESIGN FOR A GAME-BOARD.

44,588.

Specification for Design.

Patented Aug. 26, 1913.

Application filed March 15, 1913. Serial No. 754,637. Term of patent 14 years.

To all whom it may concern:

Be it known that I, JOHN H. SARGENT, a citizen of the United States, residing at Phillipsburg, in the county of Warren, State of New Jersey, have invented a new, original, and ornamental Design for Game-Boards, of which the following is a specification, reference being had to the accompanying drawing, forming a part thereof.

The figure is a plan view of a game board, showing my new design.

I claim:

The ornamental design for a game board, as shown.

JOHN H. SARGENT.

Witnesses:

JACOB BACK,
WILLIAM M. RODGERS.
